UNITED STATES PATENT OFFICE.

JOHN Q. CLARKE, OF CRAWFORDSVILLE, INDIANA, ASSIGNOR TO J. Q. CLARKE TANK CO., OF CRAWFORDSVILLE, INDIANA, A CORPORATION OF INDIANA.

PORTRABLE DRINKING FOUNT.

Application filed July 29, 1921. Serial No. 438,396.

To all whom it may concern:

Be it known that I, JOHN Q. CLARKE, a citizen of the United States, residing at Crawfordsville, in the county of Montgomery and State of Indiana, have invented new and useful Portable Drinking Founts, of which the following is a specification, reference being had to the accompanying drawings, and to the letters and figures of reference marked thereon.

This invention relates to a drinking fount that is designed to be used by animals or fowls and to supply water as needed, usually automatically, and the invention has reference more particularly to a portable drinking fount having a heating chamber whereby to temper the water and to prevent the water from freezing in winter time.

An object of the invention is to provide an improved drinking fount structure which may be advantageously produced of readily available forms of metal, such as galvanized sheet iron and standard bar shapes, which structure shall be compact and stiff without entailing cumbersome weight.

Another object is to provide a heating chamber and runners combined for drinking founts of the above-mentioned character, which shall be so constructed as to permit shipment from the factory in a compact form and with little risk of damage in transit.

A further object is to provide a drinking fount base structure which shall advantageously combine runners and heating chamber walls of such design as to permit movement on the ground from place to place without liability of damaging the heating chamber walls.

A still further object is to provide a drinking fount with a heating chamber which shall be adapted to be used in some cases by fowls, particularly small fowls as a protection from inclement weather.

With the above-mentioned and other objects in view, the invention consists in a drinking fount having a novel base structure constituting runners and a heating or housing chamber and provided with strong and dependable draft appliances of which portions constitute frame structure, enabling the structure to be easily drawn upon the ground; and, the invention consists also further in the novel parts and in the combinations and arrangements of parts as here-

inafter particularly described and further defined in the accompanying claims.

Referring to the drawings, Figure 1 is a perspective view of the drinking fount constructed substantially in accordance with the invention; Fig. 2 is a top plan of the improved fount on an enlarged scale; Fig. 3 is a front sectional elevation of the improved fount; Fig. 4 is a side elevation, partially in section, of the improved fount; Fig. 5 is a fragmentary sectional elevation showing portions of Fig. 4 on a relatively larger scale; Fig. 6 is a fragmentary sectional elevation showing details of structure approximately on the line VI—VI in Fig. 2 on an enlarged scale; and, Fig. 7 is a fragmentary section looking upward on the line VII—VII in Fig. 4 on an enlarged scale.

Similar reference characters in the different figures of the drawings indicate corresponding elements or features of construction herein referred to in detail.

The reservoir or tank for holding a supply of water may be variously constructed so as to permit the water to be fed from the lower portion thereof into a drinking trough or pan, and may comprise an inner cylindrical wall 1 and an inclosing or casing wall 2, both arranged on a bottom 3 which extends outward beyond the casing wall, the bottom in the present case being rectangular in plan, the projecting portion of the bottom forming the bottom of a drinking trough or pan and provided with a retaining wall having straight front and rear portions 4 and 5 and similar side portions 6 and 7. The inner wall 1 has a top or cover 8 secured thereto, so that the supply of water shall be covered, and any suitable provision is made for permitting the water to be fed from the lower portion of the tank into the trough or pan that extends about the casing or tank wall. A cap plate 9 is secured on top of the wall of the trough and it has a flange 10 thereon that is secured to the inner side of the wall. Suitable braces 11 are secured to the cap plate and to the wall 2.

For insuring strong support for the reservoir or tank and its load of water and obtaining a stiff base structure, four corner posts 12, 13, 14 and 15 are provided which are made of L-section angle bar. One wing of each post is partially cut away so as to leave a relatively short wing beyond which the remaining wing projects to constitute a

flat head plate 16. The shorter wings of two of the posts are arranged under the bottom 3 and the head plates of the posts extend upward against the outer side of the wall portion 4 to the under side of the cap plate 9, the remaining two posts being similarly arranged in connection with the rear wall portion 5. Two of the posts are arranged at a suitable distance inward from the side wall 6 and the remaining posts similarly arranged relatively to the wall 7. Two of the posts are suitably secured to and supported upon an L-section base bar 17 and the remaining two likewise on a base bar 18, the base bars being secured upon and constituting reinforcing parts of runner members 19 and 20 respectively, having upwardly curved forward portions 21 and 22, and also similar rear portions 23 and 24 permitting the runners to be moved backwards on the ground when necessary. A heating chamber wall plate 25 is arranged on and secured to the base bar 17 and extends upward a suitable distance against the shorter wings of two of the posts to which it is secured. A similar vertical wall portion 26 is arranged on and secured to the base bar 18 and extends upward a suitable distance against the shorter wings of the remaining two posts to which it is secured. The vertical wall portions have relatively angular wall portions 27 and 28 respectively that extend outwardly under the floor 3 to conduct heat thereto and have upwardly extending laminating wall portions 29 and 30 that extend up to the cap plate 9, and they are secured against the outer side of the side wall portions 6 and 7 respectively. The inclined side wall portions afford bracing to the portions of the bottom 3 which extend out beyond the supporting posts, and the side wall portions 6 and 7 are stiffened by the laminating wall portions 29 and 30. The heating chamber has front and rear end plates 31 and 32 respectively that are secured on the outer sides of the head plates 16 and extend from the cap plate 9 downward opposite to the front and rear portions 4 and 5 respectively, each plate having extensions 33 secured to the posts and forming angle braces which partially close the ends of the heating chamber, leaving spaces for ingress to or egress from the chamber, permitting a heating lamp to be inserted under the bottom 3 when desired.

The front curved portions 21 and 22 of the runner members have standards 34 and 35 extending upward therefrom at a distance from the front plate 31, the rearward curved portions 23 and 24 having each a similar standard 34' thereon. A tie bar 36 is secured to the outer side of the standards 34 and 35 and a similar tie bar 37 is secured to the standards 34'.

65 Preferably a supporting beam 38 is ar-

ranged under the middle portion of the bottom 3, and it has legs 39 extending downward against the wall plates 25 and 26 and the base bars 17 and 18 to which the legs are respectively secured.

A pair of draft bars and frame bars combined are provided which have main members 40 and 41 respectively that are arranged on the outer side of the wall plates 25 and 26 respectively, immediately below the angular portions thereof and are secured to the plates. One main member extends to the standard 34 and to the similar rearward standard, and the other main member extends to the standard 35 and to the similar rearward standard 34' and are respectively provided with lateral lugs 42 and 43 arranged against the forward and rearward standards respectively, and similar lugs 44 and 45 arranged against the forward and rearward standards respectively. The lugs 43 and 45 are rigidly secured to the rearward standards and also to the tie bar 37 by means of suitable devices 46 which may be rivets. The forward standards are provided with draft eyes 47 and 48 that are arranged on the front of the tie bar 36 and have shanks 49 and 50 respectively that extend through the tie bar and also through the standards 34 and 35 and the lugs 42 and 44 respectively, each shank having a nut 51 thereon to rigidly secure it in place, so that a portion of the strain in pulling is sustained by the rearward portion and also the side portions of the heating chamber structure. The eyes 47 and 48 have suitable draft chains 52 and 53 connected thereto respectively.

The heating chamber is provided with separate doors 54 and 55 to close the ends thereof when desired, the doors having securing bars 56 and 57 on the outer side thereof respectively, the doors being removably arranged at the outer side of the end plates 31 and 32 respectively, the securing bars extending beyond the adjacent standards, and being supported upon the draft bars, the ends of each securing bar preferably having a relatively angular handle 58 thereon whereby to lift the door. Each door has a suitable number of ventilating apertures 59 therein. The securing bars are arranged nearer to the top than to the bottom of the chamber door, so that when shipping the structure each door may be inverted and supported by its securing bar with its top at a safe distance from the ground and not be liable to become bent or damaged by any obstruction on the ground.

In practical use the drinking water is discharged from the reservoir or tank into the drinking trough or pan, it being preferable that the reservoir be adapted to automatically feed the water in small quantity as used. In some cases the structure is suffi-

ciently large to supply animals with water, in other cases being only large enough to supply fowls. In cold seasons the lamp is placed in the heating chamber and the doors closed to provide sufficient heat under the bottom 3, which is the top of the heating chamber, to prevent the water from freezing or to temper the water. When the heat is not necessary one of the doors of the heating chamber may be slightly elevated to permit the entrance of small fowls, or the door may be inverted and supported as in Fig. 5 to permit full grown fowls to enter the heating chamber for protection in case of storms or inclement weather. When using heat under the drinking trough or pan some of the heat passes into the space above the inclined wall portions 27 and 28, so that all portions of the top of the chamber are exposed to the heat. When it is desired to move the fount to a more desirable place for use it is readily drawn upon the ground by means of the draft chains 52 and 53, and in emergency the structure may be drawn backwards a short distance if desired, by hitching to the rearward portions of the runners. When drawing the fount over the ground the draft strains are not liable to rack the base structure since the strains through the draft bars are resisted by the most substantial portions of the structure back to the rear end thereof, so that the forward portion of the structure is not liable to be bent or distorted or torn away from the main portion of the structure.

What I claim as new is:—

1. A portable drinking fount including two runners, two opposite vertical inclosing side parts connected with the runners respectively and having each an outwardly-extending inclined upper portion, a pan connected to the upper ends of said upper portions, two end plates connected with opposite ends respectively of the pan and also with adjacent portions of the upper portions of said side parts, two draft bars secured to the outer sides of said side parts respectively, and two inclosing doors removably arranged on the outer sides of said end plates respectively.

2. A portable drinking fount including two runners, two opposite vertical inclosing side parts connected with the runners respectively and having each an outwardly-extending inclined upper portion, a water-holding pan connected to the upper end of said upper portions, two end plates connected with opposite ends respectively of the pan and also with adjacent portions of the upper portion of said side parts, two draft bars rigidly secured to said side parts respectively and connected also with the runners respectively, and two draft devices connected to the draft bars respectively and

also with the runners respectively adjacent to one end of the draft bars.

3. A portable drinking fount comprising two runners having upwardly-curved ends provided each with a vertical standard on its top, two opposite vertical side parts connected with the runners respectively and having each an outwardly-extending upper portion, a pan connected to the upper ends of said upper portions, two end plates connected with opposite ends respectively of the pan and also with the adjacent portions of said upper portions of the side parts, each end of plate being opposite to two of said standards, two draft bars secured to the side parts respectively, each draft bar being connected also to two of the standards, two draft devices connected to the draft bars respectively and also to the two standards adjacent to one end of the draft bars, and two doors on the outer side of said end plates respectively.

4. In a portable drinking fount, a heater and runner structure comprising two runners, two opposite vertical inclosing side parts secured to the runners respectively and having each an outwardly-extending inclined upper portion, a pan having a bottom connected to the upper ends of said upper portions, two end plates connected with opposite ends respectively of said bottom and also with adjacent portions of said side parts, two inclosing doors invertibly arranged on the outer sides of said end plates respectively, and a beam arranged beneath said bottom and having legs secured to the inner sides of said side parts respectively.

5. In a portable drinking fount, the combination of a base structure having two sides, two runners supporting the sides, each runner having a draft bar secured to the two opposite ends of the runner, the draft bars being secured also to said sides respectively, a pan having support on said sides, two draft eyes having connection with one end of said draft bars respectively and also with the adjacent end portions of said runners, and two doors having securing bars removably supported upon said draft bars, the doors being arranged between said runners at opposite ends respectively of said sides.

6. In a portable drinking fount, the combination with a pan, of a base structure comprising two runners, two posts supported on one of the runners, two posts supported on the remaining runner, two side wall plates connected to the runners respectively, each wall plate being connected also to the two of said posts on the runner and having an outwardly-extending upper portion connected to said pan, and two draft bars secured to the outer side of said wall plates respectively and also to end portions of said runners, each draft bar being secured also

to two of said posts and having a draft device connected with one end thereof.

7. In a drinking fount, the combination with a pan bottom, of a pan wall connected 5 to the edge of said bottom and having a broad cap plate on the top thereof, four posts having head plates secured to said wall and having each a wing portion extending under said bottom, two base bars 10 supporting said posts, two end plates secured each to two of said posts and extending to the under side of said cap plate, and two side wall plates secured to said base bars respectively and having outwardly 15 extending upper portions between said end plates, each side wall plate being secured to two of said posts, said upper portions having each a vertical portion secured to said pan wall and extending upward to said 20 cap plate.

8. In a portable drinking fount, the combination of two runners having upwardly-curved end portions, the top of each end portion having an upright standard thereon, the main portion of each runner having 25 a base bar fixed thereon, two posts secured to one of the base bars, two posts secured to the other of the base bars, two side wall plates secured to said base bars respectively

and also to the two posts thereon and having 30 each an outwardly-extending upper portion, a beam having legs secured to said wall plates, a pan supported by said posts and also upon said beam and the upper portions of said wall plates, an end plate secured to 35 two of said posts at the forward portion of the pan, an end plate secured to the other two of said posts at the rearward portion of the pan, a tie bar secured to two of said standards, a tie bar secured to the remaining 40 two standards, two draft bars secured to said side wall plates respectively, each draft bar being secured also to two of said posts and to two of said standards, two draft eyes having connections with one end of 45 the draft bars respectively and with the adjacent standards, and two invertible doors having each a securing bar secured thereto, the doors being removably arranged adjacent to the end plates respectively and the 50 securing bars supported upon the draft bars behind the adjacent standards.

In testimony whereof, I affix my signature in presence of two witnesses.

JOHN Q. CLARKE.
